COLLAPSIBLE THEFTPROOF BOTTLE
DISPLAY DEVICE

George F. Muendel, Rowayton, Conn.

Application December 19, 1938, Serial No. 246,615

9 Claims. (Cl. 211—8)

My invention relates to display devices. More particularly, it relates to the type of display device used for displaying bottles or other similar containers.

Bottles or similar containers of liquor, perfume and like contents of high value, displayed on counters, shelves, or elsewhere where the public has ready access, are subject to being surreptitiously removed or stolen, resulting in considerable loss. It is therefore one of the objects of this invention to reduce such loss to a minimum.

A further object is to provide a display device of the character described which reduces the likelihood of goods assembled thereon from being displaced and thereby damaged or rendered unattractive. Since my invention readily lends itself to decorative effects, while at the same time retaining its theft proof character, this is a further object.

A still further purpose is to provide a display device of the character described, which shall comprise relatively few and simple parts, which is collapsible to facilitate shipping and storage, which is easy to assemble, rugged in construction, of low cost, and at the same time, highly efficient in use.

Further objects will become apparent in the following detailed description thereof.

In the accompanying drawing, to which reference is had, the device is shown separate from any decorative container, such as a cardboard form of the character of a chest, in which this particular embodiment has been developed. For simplicity, the drawing shows only one bottle instead of a plurality, it being readily apparent, that following the principle of construction disclosed herein, a plurality of bottles may be safeguarded as well.

In the drawing:

Fig. 1 is a front elevational view of a completely assembled device embodying my invention, but showing only one bottle in place.

Fig. 2 is a top plan view of the device corresponding to Fig. 1.

Fig. 3 is a side elevational view of the device corresponding to Figs. 1 and 2, looking toward the hinged side of separator 31.

Fig. 4 is a front elevational view, showing the device collapsed, as for shipping or storage.

Referring now in detail to the drawing, there is shown a display device 10 embodying my invention, comprising an upper platform member 20, a lower platform member 21, spaced from each other by separator member 31, and connected

to each other at their ends by flexible strap hinges 22. These platforms 20 and 21 are further firmly held together in such spaced position by means of the bottles B which rest upon upper platform 20, and the stiff wire members 11 passing around the base of the neck of bottles B by means of loop 12, which said stiff wire members 11 pass through platform members 20 and 21 through corresponding openings 25 in each of said platform members 20 and 21, and which said stiff wire members 11 have a fastening means 13, 14, at the lower ends thereof. The entire device is raised above the level upon which it rests by any desirable means 50.

Platform members 20 and 21 are similar in layout and size, each having any desired number of openings 25 of sufficient size to accommodate stiff wire members 11 passing therethrough. Either platform member 20 or 21 may have affixed to it crosswise, a separator member 31 by such means as hinge 32. This separator member 31 may be of sufficient length to extend beyond the shorter edges of platform members 20 and 21, in at least one direction, to afford means to erect separator 31 when assembling the device. This separator member 31 is of sufficient width to separate platform members 20 and 21 to the full extent permitted by hinges 22, thereby making platforms 20 and 21 rigid with respect to each other, said platform members being held together at their ends by strap hinges 22.

Stiff wire members 11 have loops 12 at one end. These are intended to fit over the necks of bottles B resting at the base of the neck. Members 11 are of sufficient length to reach from the base of the neck of bottles B through openings 25 in platform members 20 and 21, and to be held tightly under platform member 21, when the device is assembled for display. Members 11 are held at their lower ends under platform member 21 by means of 13 and 14 consisting of an eyelet 14, in which is movably placed butterfly member 13. Butterfly member 13 is so disposed that it can lie parallel to the length of member 11 when it is desired to pass member 11 through the openings 25 in platform members 20 and 21. It is also so disposed that when it has passed through opening 25 of lower platform member 21, that it can be held perpendicular to the length of member 11 under lower platform member 21.

My invention is set up in the following manner. The device is received in the collapsed state shown in Fig. 4. Members 11 are then passed through the corresponding openings 25 of platform members 20 and 21, and member 13 caused

to lie perpendicular to the length of member 11 under lower platform 21. Bottles B are then inserted at their necks under loops 12 of member 11, the bases of said bottles resting on upper platform 20. Separator 31 is then erected. This causes the slack in members 11 above the necks of bottles B to be taken up, and bottles B are now held firmly with respect to platform member 20.

This prevents individual bottles from being removed from the display without removing the entire display which is of considerable weight. Surreptitious filching is therefore eliminated as any attempt will be detected by the noise or displacement occasioned.

It is readily seen that the entire device may be placed in a decorative container, or may be fastened to a counter or shelf. Provision can be made to keep the handle end of separator 31 inaccessible so that the platforms will not be caused to collapse.

Separator 31 may be hinged as shown, or separate and interposed between platform members 20 and 21 when assembling the display. While friction is sufficient to maintain separator 31 vertically, it is obvious that it can be fixed or locked in place.

Hinges 22 may be placed at any desirable position on members 20 and 21, or may even be dispensed with and other means used to hold the ends of members 20 and 21 together when separator 31 is placed between the platforms.

Likewise, any other means of fastening member 11 at its upper and lower extremities may be employed.

More or less variation of the exact details of construction are permissible without departing from the spirit of my invention. I desire therefore not to limit myself to the exact form of construction shown and described, but intend to point out in the claims below, all of the invention disclosed herein. It should be also understood that all the separate parts may be made of any desired materials having the properties necessary to the proper functioning of my device.

I hereby claim as new and desire to secure by Letters Patent:

1. A display device for bottles or other containers, of the character described, comprising an upper main member having an aperture and a lower main member, said upper main member being adapted to support one or more bottles or other containers thereon, means for maintaining said main members in spaced, superimposed relationship to each other, means to hold said bottle or container captive on said upper main member comprising a member adapted to receive a portion of the bottle or container and having a part thereof adapted to pass through the said aperture and to engage the lower of said main members and be held thereby.

2. A display device according to claim 1, wherein the means for maintaining the main members in spaced superimposed relationship is

also the means for moving the members relatively to each other, and renders the means to hold the bottle or other container effective when the main members are placed in spaced, superimposed relationship.

3. A display device according to claim 1, wherein the means for spacing and maintaining the main members in spaced, superimposed relationship comprises a pivotally mounted member between the main members adapted to spread the main members.

4. A display device according to claim 1, having means for limiting the relative movement of said main members.

5. A display device according to claim 1, having means comprising expansible hingelike members to limit the relative movement of the main members.

6. A display device according to claim 1, wherein the means to receive a portion of the bottle or other container comprises a looped member.

7. A display device according to claim 1, wherein the means to receive a portion of the bottle or other container comprises a looped member, a part of which engages the lower surface of the lower main member.

8. A display device of the character described, comprising an upper main member and a lower main member, both of said members having corresponding apertures, said upper main member being adapted to support a bottle or other container thereon, and means to hold said bottle or other container captive upon said upper main member, comprising a looped member to receive a portion of the bottle or container, a part of said looped member passing through the corresponding apertures in both members to engage the lower member to be held thereby.

9. A display device for bottles or other containers, of the character described, comprising an upper main member and a lower main member, the upper one of said main members being adapted to support one or more bottles or other containers thereon; means for moving the main members relatively to each other and for maintaining said main members in spaced, superimposed relationship to each other, comprising a pivotally mounted member between the main members adapted to spread the said main members.

10. The extreme spacing of said main members being limited by expansible, hinge-like members between the main members; means to hold said bottle or other container captive upon the upper main member, comprising a looped member adapted to receive a portion of the bottle or container therethrough and having a part thereof adapted to pass through corresponding apertures in said main members to engage the lower surface of the lower main member, said last named means being rendered effective when the main members are placed in spaced, superimposed relationship.

GEORGE F. MUENDEL.
